United States Patent Office

Des. 216,351
Patented Dec. 16, 1969

216,351

COMPARTMENTED COSMETICS CONTAINER

Leon J. Mitchell, 74 Forest Road, Dalston,
London, E.8, England

Filed Aug. 5, 1968, Ser. No. 13,023

Term of patent 14 years

Int. Cl. D28—03

U.S. Cl. D86—10

FIG. 1

FIG. 3

FIG. 2

FIG. 4

FIG. 5

FIG. 1 is a top plan view of a compartmented cosmetics container showing my new design;

FIG. 2 is a side elevational view thereof;

FIG. 3 is a top perspective view;

FIG. 4 is a top perspective view thereof with the compartments in a fanned out position; and

FIG. 5 is a bottom perspective view thereof.

I claim:

The ornamental design for a compartmented cosmetics container, substantially as shown.
